MEANS FOR MOUNTING CURRENT-DISTRIBUTER BLOCKS.

1,125,852.

Specification of Letters Patent.

Patented Jan. 19, 1915.

Application filed August 26, 1914. Serial No. 858,729.

To all whom it may concern:

Be it known that we, GEORGE L. LANG and ALBION D. T. LIBBY, citizens of the United States, residing at Newark and East Orange, respectively, in the county of Essex, State of New Jersey, have invented certain new and useful Improvements in Means for Mounting Current-Distributer Blocks, of which the following is a specification.

10 The object of this invention is to provide a reliable means for holding the distributer block, such as is commonly used for ignition work on internal combustion engines onto its mounting and at the same time to 15 provide a ready means for removing the distributer block from this mounting, for the purpose of inspection.

In the drawing which forms a part of this specification, Figure 1 shows a front view 20 on a reduced scale of a magneto used for ignition purposes, having the distributer block mounting thereon, and with the retaining means elevated to a position where the block may be removed. Fig. 2 is a perspective 25 view of the side and rear of Fig. 1. Fig. 3 shows the distributer block removed from the magneto and in a slightly rotated position, in order to show the three retaining studs. Fig. 4 illustrates the means used for 30 holding the block in place on its mounting.

Referring now particularly to the various figures of the drawing, in which the same designating marks refer to corresponding parts, M is a magneto, having a front plate 35 9 which has three holes through which the studs 1, 2, and 3 attached to block B, pass. The studs are grooved as indicated by 4.

7 represents two screws which screw into front plate 9 and serve to hold the yoke Y 40 in place on the rear of the plate 9, by the fact of their passing through the slots 6, in the yoke Y, at the same time they permit the yoke Y to be moved up and down by means of the turned over portion 8.

45 Assuming that the yoke Y is in the position shown in Fig. 1 the distributer block B is set in place on the front plate 9 and the yoke Y is pushed downward, so that the slots 5 therein engage the grooves 4 in the 50 studs 1, 2, and 3 of the block B. The yoke Y is given a slight "set" when it is put in place on the front plate 9 and it is therefore seen that when the block is mounted as has been described, it is locked securely in

place and when it is necessary to remove the 55 block, the yoke Y is pulled upward and the block removed.

Heretofore it has been common to use nuts, bolts and springs in various ways for holding distributor blocks in place but the 60 nuts shake off and the springs break, due to the vibration of the engines and cause more or less trouble. By our invention we eliminate these difficulties.

It will be seen that numerous changes can 65 be made in the details without departing from the spirit of our invention and the scope of the appended claims.

Having thus described our invention what we claim is;

1. In combination, a distributer block, 70 studs mounted thereon, said studs having grooves on one end thereof, a plate for receiving said block and studs and means associated with said plate for engaging the 75 grooves in said studs, thereby holding the block in position, substantially as described.

2. In combination, a distributer block, 80 studs mounted thereon, grooves in one end of said studs, a plate for receiving said block and studs, a yoke mounted on said plate and adapted to engage the grooves of said studs, whereby said block is held in position on said plate, substantially as described.

3. In combination, a distributer block, 85 studs mounted thereon, a plate for supporting said block, a yoke slidably attached to said plate, means on said studs and said yoke co-acting to hold the distributer block 90 in position on said plate, substantially as described.

4. In combination, a distributer block, 95 studs mounted thereon, grooves in one end of the said studs, a plate for receiving said block and said studs, a U-shaped member attached to said plate and having means for moving the same up and down, slots in said U-shaped member, adapted to engage the ends of said studs, whereby the distributer 100 block is held in position on said plate, substantially as described.

5. In combination, a distributer block, 105 studs mounted thereon, said studs having grooves on one end thereof, a plate for receiving said block and studs, a yoke having elongated holes therein, and means passing through said holes and secured to said plate

for holding said yoke in position thereon, and means associated with said yoke for engaging grooves in said studs, for the purpose of holding said block on said plate, substantially as described.

6. In combination, a distributor block, studs mounted thereon, said studs having grooves on one end thereof, a plate for receiving said block and studs, a yoke having elongated holes therein, and means passing through said holes and secured to said plate for holding said yoke in position thereon, slots in said yoke for engaging the grooves in said studs, whereby said block is held in place on the said plate, substantially as described.

7. In combination, a distributor block, studs mounted thereon, said studs having grooves on one end thereof, a plate for re-

ceiving said block and studs, a U-shaped yoke having slots in the ends of the two arms and a third slot at the junction of the arms, and elongated holes in the arms, screws attached to said plate and adapted to pass through the said holes, means on said U-shaped yoke for moving the same on the screws, whereby the said slots are caused to engage and disengage the annular grooves on said studs, for the purposes as described.

In testimony whereof, we have signed this specification in the presence of two witnesses.

GEORGE L. LANG.
ALBION D. T. LIBBY.
